HANDLE FOR OVEN DOOR OR THE LIKE

Jack B. Stuman, Rockford, Ill., assignor to Geo. D. Roper Corporation, Rockford, Ill., a corporation of Illinois

Application January 31, 1951, Serial No. 14,057

Term of patent 14 years

(Cl. D81—25)

To all whom it may concern:

Be it known that I, Jack B. Stuman, a citizen of the United States, residing at Rockford, in the county of Winnebago and State of Illinois, have invented a new, original, and ornamental Design for a Handle for Oven Door or the Like, of which the following is a specification, reference being had to the accompanying drawing, forming part thereof.

In the drawing:

Figures 3, 4, 5 and 6 are sections taken substantially on the section lines 3—3, 4—4, 5—5, and 6—6, respectively.

I claim:

The ornamental design for a handle for oven door or the like, substantially as shown.

JACK B. STUMAN.
